UNITED STATES PATENT OFFICE

GEORGE A. KING, OF WATERBURY, CONNECTICUT, ASSIGNOR TO SCOVILL MANUFACTURING COMPANY, OF WATERBURY, CONNECTICUT, A CORPORATION OF CONNECTICUT

TACK FASTENED BUTTON

Application filed April 3, 1931. Serial No. 527,542.

Heretofore buttons have been made which are secured to an object, such as an article of wearing apparel, by means of a tack driven into the button through its hub and the point of the tack upset or clinched within the button, and also wherein the tack has been engaged by an anvil within the button without upsetting or clinching the tack point.

The present invention relates to the second mentioned type of tack-fastened buttons, and it consists in using a tack-engaging element or anvil having resilient means which frictionally engage the shank of the tack and also having other parts to engage the shank above the friction means to steady the tack and prevent undue tipping of the button, the said element being positively held in stable upright position in the hub of the button, as I will proceed now more fully to explain and finally claim.

In the accompanying drawings illustrating the invention, in the several figures of which like parts are similarly designated, Figure 1 is a side elevation of a button head showing one form of stabilizing means, and Fig. 2 is a similar view showing another form of stabilizing means. Fig. 3 is a longitudinal cross-section of the button head of Fig. 1 with the inserted tack-engaging element or anvil and a thumb-tack in position of entry therewith arranged below it. Fig. 4 is a longitudinal cross-section showing the button head of Fig. 2 and the inserted tack-engaging element or anvil. Fig. 5 is a view like Fig. 3 with the tack inserted and an interposed piece of fabric on which the button and tack are fastened. Fig. 6 is a top plan view of the tack-engaging element or anvil; Fig. 7 is a bottom plan view thereof, and Fig. 8 is an elevation of the said element or anvil.

As illustrating the invention I have shown a sheet metal button head of conventional shape, having a back 1, made integral with a hollow or tubular hub 2, and a cap or face plate 3 closed over the rim of the back. The hub is provided with a perforation 4 for the entrance of the tack by which the button is attached to an object, 5, Fig. 5, such as an article of wearing apparel. The tack prefer-

ably employed, is of the thumb-tack type, 6, shown in Figs. 3 and 5.

The tack-engaging element or anvil shown in Figs. 3 to 8 inclusive, is made of relatively thin spring steel, and comprises a circular disk-like base 7, having a central perforation 8 from which radiate slits 9 forming a series of resilient fingers 10 having arcuate free ends to engage the shank of the tack. The base is coned upwardly with the apical end 55 at the perforation 8, so that when the button is attached to or set upon an article, as shown in Fig. 5, the shank of the tack in being forced into the button through the perforation 8 will cause the spring fingers 10 to yield sufficiently to let it pass and into engagement with said fingers, the arcuate edges of the fingers thus frictionally engaging such shank and being in position to bite the same and resist any tendency of the withdrawal of the tack. This 70 biting tendency of the spring fingers and the gripping power of the tack-engaging member is enhanced by the conical formation of the member, since the fingers assume a more acute angle relatively to the tack shank than 75 as presented by the original before insertion of the tack shank.

The base 7 is provided with the upstanding arms 11 rising oppositely to one another from the rim of the base and of transverse curvature, and converging at their upper ends and made arcuate at such ends, as at 12, to embrace the upper portion of the shank of the tack and hold the parts in anti-tipping relation. 80

In order adequately to stabilize the tack-engaging element or anvil within the button head, the hub is provided with indentations which overlie the edge of the base 7 and force the element into close contact with the bottom of the hub. Such indentations may be punch marks or pricks 13, Figs. 1, 3 and 5, or somewhat elongated punch marks 14, Figs. 2 and 4. By making the tack-engaging element of thin metal and arranging its base 7 85 in the bottom of the hub, these indentations may be made in the hub at points that will not interfere with the freedom of buttoning and unbuttoning or present points to catch in the buttonhole. 90

In my case Serial No. 445,409, filed April 18, 1930, I have shown a tack-engaging element of substantially the construction of the tack-engaging element of this case applied in a snap fastener element, but I am not aware that such an element has heretofore been applied to and made a part of a button.

Variations in details of construction are permissible within the principle of the invention and the scope of the claims following.

What I claim is:—

1. A button utilizing a thumb-tack to fasten it to a garment or other object, said button comprising a button head provided with a hollow hub in the bottom of which is arranged a thumb-tack-engaging element having a coned, slitted and perforated base adapted to engage the shank of the tack near the head of the tack and having fingers extending from said base and opposite one another and shaped to conform to the shank of the tack and engage with and support the same in position substantially normal to the bottom of the button hub, the base of said element being stabilized and secured in fixed relation to the bottom of said hub by means of punch marks forming indentations in the tubular portion of the hub adjacent and in close proximity to its bottom and above the base of the engaging element and in engagement therewith, the relative thinness of said base permitting location of said punch marks out of the zone of operative usefulness of the hub when the button is in use.
2. A button utilizing a thumb-tack to fasten it to a garment or other object, said button comprising a button head provided with a tubular hub in the bottom of which is arranged a thumb-tack-engaging element having a coned, slitted and perforated base made of thin resilient material adapted to engage the shank of the tack near the head of the tack and having fingers extending from said base and opposite one another and shaped to conform to the shank of the tack and engage with and support the same in position substantially normal to the bottom of the button hub, the base of said element being stabilized and secured in fixed relation to the bottom of said hub by means of punch marks forming indentations in the tubular portion of the hub adjacent and in close proximity to its bottom and above the base of the engaging element and in engagement therewith.

In testimony whereof I have hereunto set my hand this 2d day of April A. D. 1931.

GEORGE A. KING.
